(57) **CLAIM**

The ornamental design for a windshield wiper bracket, as shown and described.

DESCRIPTION

FIG. 1 is a front, right perspective view of a windshield wiper bracket showing my new design;

FIG. 2 is a right side view thereof;

FIG. 3 is a left side view thereof;

FIG. 4 is a top plan view thereof;

FIG. 5 is a bottom plan view thereof;

FIG. 6 is a front view thereof; and,

FIG. 7 is a rear view thereof.

The dotted line structure forms no part of the invention.
